(57) CLAIM

We claim, the ornamental design for a display screen or portion thereof with graphical user interface, as shown and described.

DESCRIPTION

The FIGURE is a front view of a display screen or portion thereof with graphical user interface showing our new design.

The broken lines are for environmental purposes only and form no part of the claimed design. It should be appreciated that at least a portion of the display screen is shown inside the outer broken lines.

1 Claim, 1 Drawing Sheet
